GAME BOARD

Harold N. Wright, Seattle, Wash.

Application October 30, 1959, Serial No. 58,128

Term of patent 14 years

(Cl. D34—5)

Fig. 1

Fig. 2

Fig. 3

Fig. 4

Fig. 5

Fig. 1 is a perspective view of a game board disclosing my design.

Fig. 2 is a top plan view of the game board.

Fig. 3 is a side view of the game board.

Figs. 4 and 5, respectively, are front end and rear end elevations of the board.

I claim:

The ornamental design for a game board, as shown.
